MACHINE BRAKE.

No. 363,441.

Patented May 24, 1887.

UNITED STATES PATENT OFFICE.

GOTTLOB WARTTINGER, OF BERLIN, GERMANY.

MACHINE-BRAKE.

SPECIFICATION forming part of Letters Patent No. 363,441, dated May 24, 1887.

Application filed April 15, 1886. Serial No. 198,918. (No model.) Patented in England April 1, 1886, No. 4,593; in Belgium April 15, 1886, No. 72,634; in France August 9, 1886, No. 175,262, and in Austria-Hungary September 13, 1886, No. 13,826 and No. 41,306.

To all whom it may concern:

Be it known that I, GOTTLÖB WARTTINGER, of the city of Berlin, in the Kingdom of Prussia and Empire of Germany, have invented new and useful Improvements in Brakes, (for which I have obtained Letters Patent in the following countries: in France, No. 175,262, dated August 9, 1886; in Belgium, No. 72,634, dated April 15, 1886; in Austria-Hungary, No. 13,826 and No. 41,306, dated September 13, 1886, and in Great Britain, No. 4,593, dated April 1, 1886,) of which the following is a specification.

This invention relates to certain new and useful improvements in brakes for use on hoisting apparatus and like devices; and the object of my invention is to provide a brake which is simple in construction, operates automatically, rapidly, and effectively, and which is not apt to get out of order.

The invention consists in the combination, with two circular plates of which one is fastened on the winding-drum and the other surrounds the first loosely, of balls placed in tapering ways in the outer circular plate and running on a circular track of the inner plate, brake-blocks being provided for engagement with the outer circular plate, as will be fully described and set forth hereinafter, and finally be pointed out in the claims.

In the accompanying drawing, Figure 1 is a side view of a hoisting apparatus provided with my improved brake. Fig. 2 is a longitudinal sectional view of the same, parts being broken out. Fig. 3 is a plan view of the same. Fig. 4 is an enlarged detail sectional view of one end of the drum and brake. Figs. 5 and 6 are cross-sectional views through the two circular plates on which the balls revolve.

Similar letters of reference indicate corresponding parts.

The main shaft A is journaled in a frame, A', and carries a fly-wheel, S. On said shaft the winding-drum H is mounted loosely and is provided at one end with a clutch-disk, E, with which a clutch-disk, C', can engage, said clutch-disk C' being mounted to revolve with the shaft and to slide on the same, and is held in the forked end of a lever, D, pivoted on the

frame A', by means of which lever the clutch-disk C' can be moved toward or from the clutch-disk E on the winding-drum H. On one end of the winding-drum H the disk F is secured, and is connected with the clutch-disk E by a rod, G, passed longitudinally through the winding-drum H. Said disk F is provided on its outer surface with an annular track, f, projecting from the disk concentric with the shaft A. A circular plate or disk, F', is provided on the surface that faces the disk F with a hub, F', and with the three ways, x y z, which are all tapered in the same direction for about two-thirds of their length. In the said ways the balls x' y' z' are placed, which run on the annular track f of the plate F. At the highest part of the tracks x, y, and z their height is greater than the diameter of the balls; but those sides of the ways opposite the annular track f gradually converge toward the said track f, as shown in Figs. 5 and 6.

Brake-blocks K or brake-bands rest on the flange w of the disk F', and are connected by suitable devices with a lever, L, having the weight M, in place of which weight a spring may be used.

To exclude the dust, &c., the disk or plate F is provided with a circular spline, o, which passes into a groove, p, in the outer edge of the flange w. The disks F F' are mounted loosely on the shaft A.

The operation is as follows: The shaft A revolves in the direction of the arrow, Fig. 5, when the load is to be raised. By means of the lever D the clutch-disk C' is engaged with the clutch-disk E, whereby the same will also be revolved in the direction of the arrow, Fig. 5. The balls x' y' z' remain in the lowest parts of the pockets x y z and run loosely in the same on the outer surface of the track f. When it is desired to lower the load and uncoil the rope from the drum, the clutch-disk C' is disengaged from the clutch-disk E, when, under the action of the load, the drum is revolved a short distance in the direction of the arrow, Fig. 6, whereby the balls x' y' z' run toward the narrower parts of the ways and bind against the opposite surface of the track f and ways, whereby the disks F F' are connected to revolve together. As

the disk F' is held by the brake-blocks or the brake-band, under the action of the weight M, the disk or plate F and the winding-drum are also held. By raising the weight M the brake-blocks are disconnected more or less from the disk F', thus permitting the disks F F' and the winding-drum H to revolve in the direction of the arrow, Fig. 6. If then the drum H is revolved in the direction of the arrow, Fig. 5, by turning the shaft A and engaging the clutch-disks C and E the balls x' y' z' run to the wider ends of the pockets or ways x y z, and the drum H and disk F can revolve without revolving the disk F'.

To facilitate the gripping of the balls the surface of the ways or tracks are preferably rifled or roughened in any other suitable manner. The balls x y z are preferably made of elastic material, with or without a non-elastic core.

This brake can be used for windlasses, hoisting-drums, or any other machinery in which the movements are to be checked automatically.

Having thus described my invention, I claim as new and desire to secure by Letters Patent—

1. The combination, with a drum, of a disk secured on the end of the same, balls on part of said disk, and a loose disk adjacent to the disk on the end of the drum, which loose disk is provided with pockets or ways for the balls on the disk fastened on the end of the drum, and brake-blocks or brake-bands for holding the loose disk, substantially as shown and described.

2. The combination, with a winding-drum, of a disk on the end of the same, balls on said disk, a disk placed adjacent to the disk on the end of the drum and provided with compartments for receiving the balls, a brake band or blocks on the upper surface of the loose

disk, and a weighted lever connected with said brake-blocks, substantially as shown and described.

3. The combination, with a winding-drum, of the disk F, secured to the end of the same and provided with an annular track projection, f, a loose disk, F', provided with a flange, w, and having pockets or ways x y z, and the balls x' y' z', running on said track projection f and in the pockets or ways, and brake-blocks connected with the frame, substantially as shown and described.

4. The combination, with the shaft A, of a winding-drum mounted loosely on the same and provided with the clutch-disk E, a sliding clutch-disk, C, on the shaft, the disk F on the end of the drum and provided with the circular track projection f, the disk F', mounted loosely on the shaft and provided with ways or pockets for receiving balls running on the circular plate F, and brake bands or blocks on the rim of the disk F', substantially as shown and described.

5. The combination, with a winding drum, of the disk F on the end of the same, provided with a circular spline, o, and a circular track projection, f, the loose disk F', provided with pockets for receiving balls that run on the track projection f of the disk F, the said disk F having a flange, w, provided in its circular edge with a circular groove, p, for receiving the spline o, and brake blocks or bands on the disk F', substantially as shown and described.

In testimony that I claim the foregoing as my invention I have signed my name in the presence of two witnesses.

GOTTLOB WARTTINGER.
